(57) **CLAIM**

The ornamental design for a seat arrangement, as shown and described.

DESCRIPTION

FIG. 1 is a perspective front view of the seat arrangement embodying the present invention.

FIG. 2 is a right side elevational view of the seat arrangement embodying the present invention.

FIG. 3 is a front elevational view of the seat arrangement embodying the present invention.

FIG. 4 is a left side elevational view of the seat arrangement embodying the present invention.

FIG. 5 is a top elevational view of the seat arrangement embodying the present invention; and,

FIG. 6 is a rear elevational view of the seat arrangement embodying the present invention.

The broken lines in the FIGURES represent portions of the seat arrangement that form no part of the claimed design.

1 Claim, 6 Drawing Sheets
